ODORIZING LAMP

Peder Larsen, Canton, Ohio

Application December 15, 1933, Serial No. 702,552

7 Claims. (Cl. 240—2)

The invention relates to a lamp for vaporizing a volatile perfume or deodorant and diffusing the same into the atmosphere of a room or other enclosure.

5 The object of the invention is to provide a device including a source of heat which causes air to rise and to flow by, against, around or through a body of substance containing a volatile perfume or deodorant.

10 Another object is to provide a lamp including a vaporizer combined with indirect or direct lighting or a combination of both.

A further object of the invention is to provide such a device in which the substance containing 15 the volatile perfume or deodorant is located in a direct route of air to or from the source of heat.

The above and other objects which will be apparent from an examination of the drawing and the following description, or which may be later 20 pointed out, may be attained by constructing the odorizing lamp in the manner illustrated in the accompanying drawing, in which

Figure 1 is a vertical sectional view of a lamp embodying the invention, showing a form of the 25 improved lamp adapted to be placed upon a table or the like;

Fig. 2, a side elevation of a floor lamp embodying the invention;

Fig. 3, an enlarged vertical sectional view of 30 the form of lamp shown in Fig. 2;

Fig. 4, a detail sectional view showing the valve for controlling the flow of air, taken as on the line 4—4, Fig. 1; and

Fig. 5, a longitudinal sectional view through 35 the valve, taken as on the line 5—5, Fig. 3.

Similar numerals refer to similar parts throughout the drawing.

The invention includes a housing which forms a shade for the light, and may be constructed 40 so as to provide either direct or indirect lighting or both. Within the housing is mounted a source of heat and light and means cooperating therewith for causing a current of air to circulate through the housing, a body of substance containing a volatile perfume or deodorant being located in a direct route of air to or from the source of heat.

In the form of the invention shown in Fig. 1 is illustrated a lamp arranged to be placed upon 45 a table or the like and constructed so as to provide both direct and indirect lighting. For this purpose, the housing or shade 10 is opaque and may be made of sheet metal or the like and the upper open end thereof is flared or bell-shape, 55 as shown at 11.

The source of heat, and also of light, may be in the form of an incandescent light bulb 12 located within the upper portion of the shade or housing 10 and mounted within the usual socket 13, which may be supported by a clamp ring 14 having arms 15 formed thereon or attached thereto and connected to the inner walls of the shade or housing 10 by any suitable and well known manner such as spot welding or the like.

The wires 16 leading to the socket 13 may be 60 connected to an electric cord 17 of usual construction which may pass through an opening 18 in the lower portion of the housing or shade 10 and may be provided with an attaching plug 19, as in usual practice, for connection to a suitable base receptacle or the like. A switch of any suitable construction, indicated generally at 20, may be located in one side of the housing or shade 10 and interposed between the socket 13 and the cord 17 for controlling the operation of the incandescent 70 bulb 12 in usual and customary manner.

Although the body of substance containing the volatile perfume or deodorant may be located at any point within the housing in a direct route of air to or from the source of heat, for the purpose 80 of illustration, the same is shown in the drawing as located below the source of heat and so arranged that it may be in a direct route of air to the source of heat.

For this purpose a tube 21 may be located within 85 the lower portion of the housing 10, one end thereof butting tightly against the adjacent inner wall of the housing as at 22, the other open end thereof being preferably spaced from the opposite wall of the housing as shown at 23.

In order to secure the tube 21 in position, a rivet or the like as indicated at 24 may be located 90 through the bottom wall of the tube and through a corresponding portion of the bottom wall 25 of the housing 10. The bottom walls of the tube and housing may be concaved at the point where the rivet is located as indicated at 26 in order to provide an unobstructed interior for the tube and a flat unobstructed bottom for the housing 10 so that 95 the same may rest upon a table or other horizontal surface.

An opening 27 is provided in the side wall of the housing 10 in position to register with the open 100 end 23 of the tube 21 and the body of substance containing the volatile perfume or deodorant is adapted to be inserted through the opening 27 and into the open end 23 of the tube.

For this purpose a vial 28 may be provided for containing the volatile substance. The vial may 110 contain cellulose or other suitable fibrous mate-

rial, impregnated with the volatile perfume or deodorant, as shown at 29. The tube 21 may be provided near its other end with an indentation as shown at 30 to act as a stop to limit the position of the vial therein and the vial may be retained in position by means of the cover plate 31 which fits over the opening 27 and is held in position as by the spring catch 32, a washer 33 of rubber or the like being preferably provided upon the inner side of the cover plate to engage the closed end of the vial 28.

An opening 34 is provided in the upper wall of the tube 21 adjacent to the open end of the vial 28 and a valve may be provided in this end portion 15 of the tube. This valve may be substantially cup-shaped as indicated at 35 and of such size that it has a turning fit within the tube 21. One side of the open end portion of the valve may be bent inward or reduced as at 36 so that when the same 20 is turned to the position shown in Figs. 1 and 4, the opening 34 in the upper wall of the tube is uncovered.

It will be seen that by rotating the valve until this reduced portion 36 thereof is moved away 25 from the opening 34, the straight or cylindric portion of the cup-shaped valve will register with the opening 34 entirely closing the same.

An opening 37 is formed in the end wall of the cup-shaped valve 35 and is arranged to register 30 with a similar opening 38 in the adjacent side wall of the housing 10 when the valve is in the open position as shown in Figs. 1 and 4. The knob 39 is provided with a reduced portion journaled through the side wall of the housing 10 and fixed to the end wall of the valve 35 so that by 35 rotating said knob the valve may be turned to open or closed position.

It will be seen that the light from the incandescent bulb 12 will be directed upward through 40 the upper open end of the shade or housing 10, producing an indirect lighting and if it is desired to provide direct lighting, transparent or translucent panels of any desired size, shape or design, as indicated generally at 40, may be provided in suitable openings 41 which may be formed in the side walls of the housing 10 for that purpose. If desired, the shade or housing 10 may be formed of glass or other transparent or translucent material.

50 As shown in Figs. 2 and 3, the improved deodorizing lamp may be in the form of a floor lamp, in which case the shade or housing indicated generally at 10' may be supported upon a pedestal adapted to stand upon the floor.

55 This pedestal may comprise a spacing sleeve or tube 43 located between the housing or shade 10' and the base indicated generally at 44, the upper end of said tube surrounding the depending reduced neck 45 formed at the lower end of the housing 10', and abutting the shoulder 46 60 upon the housing at the upper end of said neck, while the lower end of the tube surrounds the reduced upwardly extending neck 47 upon the base 44 and abuts the shoulder 48 at the lower end of said neck.

A tie rod 49 is located within the tube 43, the lower end of the tie rod extending through a central opening 50 in the base 44 and being provided with a nut 51 while the upper end of the 70 rod extends through a conical block 52 located within the tapered throat 53 of the housing, a nut 54 being mounted thereon for tightly clamping the housing 10' and base 44 together upon the spacing tube 43.

75 The incandescent light bulb 12' may be lo-

cated within the upper portion of the shade or housing 10' and mounted within a socket 13' supported within the central annular flanged portion 14' of the cup-shaped bracket 15' which may be connected to the inner walls of the housing by any suitable and well known manner such as spot welding or the like, and which is provided with one or more openings 15'' in order to provide for a passage of air upward through the housing 10'. 80

The electric cord 17' of usual construction may be connected to the socket 13' and extended through an opening 18' in the lower portion of the housing 10' and is provided at its end with an attaching plug 19' as in usual practice, for connection to a suitable base receptacle or the like. The socket 13' may be of the form usually provided with a chain pull switch and the chain 20' thereof may be located through an opening 20'' in the side of the housing 10' and provided with a knob or button 20''' for manipulating the switch. 85

The body of substance containing the volatile perfume or deodorant may be located at any point within the housing in a direct route of air to or from the source of heat, and for the purpose of illustration the same is shown as located below the incandescent bulb 12' and so arranged that it may be in a direct route of air thereto. 90

The tube 21' may be located within the lower portion of the housing 10', one end thereof butting tightly against the adjacent inner wall of the housing as at 22', the other open end thereof being preferably spaced from the opposite wall 105 of the housing as indicated at 23'. 110

This tube may be secured in position within the housing by means of the ears 22'' formed at the end 22' of the tube and spot welded or otherwise attached to the adjacent inner wall 115 of the housing 10'. 120

An opening 27' may be provided in the side wall of the housing 10' in position to register with the open end 23' of the tube, and the body of substance containing the volatile perfume or deodorant may be inserted through the opening 27' and into the open end 23 of the tube. 125

A vial 28' may be provided for this purpose and may contain cellulose or other suitable fibrous material impregnated with the volatile perfume or deodorant as indicated at 29'. 130

An indentation 30' may be formed near the other end of the tube to act as a stop to limit the position of the vial within the tube and the vial may be retained in position by means of the cover plate 31' which fits over the opening 27'. 135 and is held in position as by the spring catch 32'. 140

The upper wall of the tube is provided with an opening 34' adjacent to the open end of the vial and a valve may be provided in this end portion of the tube similar to the valve 35 shown in Figs. 1 and 4. This valve is indicated generally at 35', being substantially cup-shaped as above described and of such size that it has a turning fit within the tube 21'. One side of the open end portion of the valve may be bent inward or reduced as at 36' and an opening 37' may be formed in the end wall of the valve and arranged to register with a similar opening 38' in the adjacent side wall of the housing 10' when the valve is in the open position as shown in Fig. 3. A knob 39' may be provided for manipulating the valve, the operation of which is identical with that of the valve 35 above described. 145

From the above it will be evident that the 150

light from the incandescent bulb 12' will be directed upward through the upper open end of the shade or housing, producing an indirect lighting effect. It should be understood that a direct lighting effect may be produced in this floor lamp type of the invention in the same manner as illustrated and described with reference to the form of the invention shown in Fig. 1.

The operation of both forms of the invention is the same. With the valve open, air enters through the opening in the side wall of the housing, passing through the cup-shaped valve and against or in contact with the body of substance containing the volatile perfume or deodorant and is then drawn upward through the opening in the top of the tube 21 or 21', as the case may be, and through the upper portion of the housing or shade and out of the upper open end thereof, the heat from the incandescent bulb causing a continual circulation of air, cold air being drawn in at the lower end of the housing where it picks up the odor of the volatile perfume or deodorant and then rises through the housing or shade as it becomes heated.

Although the invention has been illustrated and described as an odorizing lamp for the purpose of furnishing light and at the same time vaporizing a perfume or deodorant, it should be understood that the invention may also be used simply as a vaporizer with any other form of electric resistance than an incandescent bulb, and instead of vaporizing a perfume or deodorant, the housing may contain a volatile insecticide such as is used for destroying moth and other insects.

I claim:

1. An odorizing lamp including a housing, a body of substance containing a volatile material within the housing, a source of heat within the housing for causing air to flow through the housing and to contact with said body of substance, and a valve for controlling the flow of air through the housing.

2. An odorizing lamp including a housing open at its upper end, a source of light and heat within the housing for producing an indirect lighting effect through the open end thereof, means for admitting air to the lower portion of the housing

whereby the source of light and heat will cause the air to rise and pass out of the upper open end of the housing, and a body of substance containing a volatile material and located in the path of the air through the housing, and a valve located in said path of air.

3. An odorizing lamp including a housing having an opening at its upper end, an incandescent bulb within the housing, a tube located within the housing, means for admitting air to one end of the tube, a body of substance containing a volatile material within the other end portion of the tube, there being an opening in the tube adjacent to said body of substance.

4. A vaporizing device including a housing, a container located within the housing, a body of volatile substance in said container, valves in the container controlling air passages to and from said body of volatile substance, and a source of heat within the housing for causing air to flow through the housing and to contact with said body of volatile substance.

5. A vaporizing device including a housing, a body of volatile substance containing an odorant, deodorant or insecticide in a container, said container being at least partly perforate, means for closing said container at times for preventing air flow from the container, and a source of heat within the housing for causing air to flow through the housing adjacent to said body of volatile substance.

6. A vaporizing device including a container, a body of volatile substance in said container, a valve in the container for controlling air passages to and from said body of volatile substance, and a source of heat associated with the container for causing air to flow through the valve and to contact with said body of volatile substance.

7. A vaporizing lamp including a housing closed at its lower end and having an opening at its upper end, an incandescent bulb within the upper portion of the housing, a tube located in the lower portion of the housing, a body of volatile substance within the tube, there being an opening in the housing registering with one end of the tube and an opening in the side of the tube, and a valve for controlling said openings.
